UNITED STATES PATENT OFFICE.

WALTER M. SCHWARTZ AND WILLIAM D. PALEN, OF PHILADELPHIA, PENNSYLVANIA,
ASSIGNORS TO THE PHILADELPHIA TEXTILE MACHINERY COMPANY, OF PHILA-
DELPHIA, PENNSYLVANIA, A CORPORATION OF PENNSYLVANIA.

CONVEYING APPARATUS FOR DRYING-MACHINES.

No. 877,801.

Specification of Letters Patent.

Patented Jan. 28, 1908.

Application filed September 19, 1907. Serial No. 393,591.

To all whom it may concern:

Be it known that we, WALTER M. SCHWARTZ and WILLIAM D. PALEN, citizens of the United States, residing in Philadelphia, Pennsylvania, have invented certain Improvements in Conveying Apparatus for Drying Machines, of which the following is a specification.

Our invention relates to certain improvements on conveying apparatus for drying machines, and especially for machines for drying veneers.

The object of our invention is to so construct the endless chain conveyors for carrying the material that the cross-bars will be suitably braced in order to remain a given distance apart and to resist the tendency of the veneer or other material being dried to bend the bars when drying. These objects we attain in the following manner, reference being had to the accompanying drawing in which:

Figure 1 is a transverse sectional view of a veneer drying machine illustrating our invention. Fig. 2 is a plan view of a portion of the endless chain conveyor illustrated in Fig. 1; Fig. 3 is a transverse sectional view on the line 3—3 Fig. 2; Fig. 4 is a sectional view on the line 4—4, Fig. 2; Fig. 5 is a section on the line 5—5 Fig. 4, showing a part of one of the cross-bars in section; and Figs. 6 and 7 are views showing modifications of the form of cross-bar.

In illustrating our invention, we have simply shown a transverse sectional view through the veneer drying machine, as the present invention relates to the construction of the endless chain conveyor and a sectional view is sufficient to illustrate the application of our invention to a drying machine.

While we have shown the invention applied to a veneer drying machine, it will be understood that the invention can readily be applied to machines for drying other material such as paper pulp, binder board, and in fact any material which must be held flat during the drying process.

A is a casing containing the drying chamber B and the air heating chambers C—C. In the present instance there is a heating chamber at each side of the drying chamber.

c are steam pipes for heating the air as it passes through the chambers C.

e is a circulating fan mounted on a shaft E driven by any suitable means and there may

be as many of these fans as desired throughout the length of the machine. The fans cause the air to circulate through the heating and drying chambers C and B, as the material is conveyed longitudinally through the machine.

In the present instance, we have shown five endless chain conveyors D, one mounted above another, and these conveyors are adapted to tracks a longitudinally secured to the side walls of the drying chamber B. In the present instance the upper run of each chain supports the lower run of the chain above it so that the distance between the lower run of one chain and the upper run of the other will be always the same, but in some instances the lower run of the chains may travel on independent tracks if desired.

The type of apparatus in which we have illustrated our invention is clearly shown in the application filed by Frederick Kukkuck September 13, 1906, for improvements in feeding mechanism for drying machines, Serial No. 334,448.

Each endless chain is made up of a series of links d connected by pivots at d' and the abutting surfaces of the links are flat so that the links on the lower run of one chain will rest upon those of the upper run of another chain.

Mounted on the pivot pins of each chain are rollers d² which are so proportioned as to rest upon the tracks a so as to materially reduce the friction. Each conveyor consists of two chains one on each side of the drying compartment as illustrated in Figs. 1 and 2 connected together at short intervals by transverse members i consisting in the present instance of tubular bars which rest in bosses d³ projecting from the links of the chain and are of such diameter as to leave a space x of a sufficient height to accommodate the veneer or other material to be dried, allowing it freedom to expand and contract but preventing it warping.

Veneer drying machines are usually of considerable width and it is difficult to maintain the cross bars the same distance apart throughout the entire width of the machine when the veneers are drying, as heavy veneers particularly will in many cases bend the bars in their endeavor to warp. We overcome this tendency by making each of the cross-bars in the form of a girder, truss-

ing it so as to resist the tendency of the veneer to press them apart and thus the veneer is held so that it cannot warp, and furthermore, we are enabled by our invention to maintain the cross bars always the same distance apart. There may be many different ways of constructing the conveyer and in Figs. 2, 3, 4 and 5 we have shown one method which we prefer to use.

10 10 *n* is a rod which is adapted to a notch *i* in each end of the tubular cross bar *i* as indicated in Fig. 5, and the end *n'* of this rod is bent by forcing a tool into the end of the tubular bar *i* so that the end will assume the

15 hooked-position shown clearly in Fig. 5, and the rod *n* passes through eyes on strut members *m*—*m* projecting from the tubular cross bar *i* as illustrated in Figs. 1 and 3. Thus the entire conveyer as well as each cross bar 20 is firmly braced so that when the two chains come together as in Fig. 3 the space *x* between the cross-bars of the two chains will be the same throughout the width of the conveyer.

25 In some instances the cross-bar and the brace may be made in one piece as shown in Fig. 6, which illustrates a metal sheet bent up in cruciform shape in cross section, thus forming a cross-bar *i*³ which is attached to the 30 side chains.

In Fig. 7 is shown the cross bar *i*³ made in one piece with the truss member enlarged at the bearing point and having a sufficient web to brace it throughout its entire length.

35 Other forms of braces can be used in carrying out our invention, although we prefer the construction illustrated in Figs. 2 to 5, both inclusive.

We claim:—

40 1. An endless chain conveyer consisting of side members connected together at intervals by truss members, substantially as described.

45 2. In a conveying apparatus, the combination of two endless conveyers, one mounted above the other and each consisting of side members and trussed cross members, substantially as described.

50 3. The combination in conveying apparatus for drying machine, of two endless belt conveyers, one mounted above the other, each conveyer having a chain at each side connected by trussed cross members spaced apart, the cross members of one chain being directly above the cross members of the other chain on the carrying run, substantially as described.

55 4. The combination in a conveyer, of two

longitudinal chains, transverse members connecting the chains together at intervals, with 60 braces at the back of each transverse member extending from one side of the conveyer to the other, substantially as described.

5. The combination in a conveying apparatus for drying machines, of two or more 65 endless belt conveyers, one mounted above another, each conveyer having side chains and trussed cross members, the trusses being so arranged as to resist the outward pressure of the material carried between the belts, 70 substantially as described.

6. The combination in a conveying apparatus for drying machines, of an endless conveyer consisting of two side chains connected together by a series of transverse members, 75 said transverse members being tubular, and a brace consisting of a rod attached to the tubular member at each end and struts mounted between the transverse member and the rod so as to stiffen the transverse member, substantially as described.

7. The combination in a conveying apparatus for drying machines, of an endless conveyer consisting of two side chains, a tubular transverse member extending from 85 one chain to the other, said transverse member having an opening near each end, a rod running parallel with the transverse member hooked at each end and adapted to the openings in the transverse member, and a strut 90 member extending from the transverse member to the rod, substantially as described.

8. The combination in a conveying apparatus for drying machines, of an endless chain conveyer consisting of two side chains 95 formed of links pivotally connected together by bosses on each link between the pivots, tubular transverse members mounted in the bosses and extending from one side of the conveyer to the other, the said tubular cross 100 member having holes near each end, a brace rod extending parallel with the transverse member, the ends of the rods extending through the holes and bent to form hooks, and strut members extending from the 105 transverse member to the brace rod, substantially as described.

In testimony whereof, we have signed our names to this specification, in the presence of two subscribing witnesses.
